UNITED STATES PATENT OFFICE.

JAMES L. WELLS, OF EL PASO, TEXAS.

APPARATUS FOR UTILIZING HOT SLAG FOR HEATING PURPOSES.

SPECIFICATION forming part of Letters Patent No. 657,843, dated September 11, 1900.

Application filed December 16, 1899. Serial No. 740,583. (No model.)

To all whom it may concern:

Be it known that I, JAMES L. WELLS, a citizen of the United States, residing at El Paso, in the county of El Paso and State of Texas, 5 have invented certain new and useful Improvements in Apparatus for Utilizing Hot Slag for Heating Purposes, of which the following is a specification.

This invention relates to apparatus for utilizing hot slag for heating purposes, its object being to so construct a receptacle that the molten slag may be applied to and held in contact with the exterior surface of the receptacle and be easily discharged therefrom 15 when necessary.

In the accompanying drawings I have illustrated my invention as applied to a steam-generator and to a hot-blast apparatus; but it is evident that it may be applied to receptacles for other purposes, and hence I do not limit the invention to such uses.

In the accompanying drawings, Figure 1 is a side elevation of a steam-generator embodying my invention, some parts being omitted 25 to more clearly show the construction of other parts. Fig. 2 is a transverse section on the line 2 2 of Fig. 1. Fig. 3 is a similar section on the line 3 3 of Fig. 1. Fig. 4 is a side elevation of a hot-blast apparatus embodying 30 my invention; Fig. 5, a transverse section on the line 5 5 of Fig. 4, and Fig. 6 a horizontal section of a portion of Fig. 4. Fig. 7 is a sectional detail of the sliding rod and its guide, shown in Figs. 3 and 5.

35 In carrying out my invention I provide a series of chambers on the exterior of the receptacle and partially surrounding it, one side of each chamber being movable for the purpose of discharging the slag and each chamber having a filling-aperture. These chambers may be formed in many ways and be of 40 any desired shape, provided they be entirely on the exterior of the receptacle, and while the construction illustrated in the drawings 45 and to be now described is preferred it must be understood that my invention is not limited to such construction.

Referring to Figs. 1, 2, and 3, it will be seen that the generator consists of a cylindrical 50 portion or shell A, having the usual steam-dome a and a series of ribs or projections B.

These ribs or projections are hollow and extend nearly around the shell A, and each is connected at its lower portion to a blow-off pipe C by means of a pipe b. They may be 55 secured to the shell in any desired manner and will be in communication with the interior of the shell through openings 10 and 11, so that the water in the generator will circulate freely through them and the shell. 60

The ribs or projections B are spaced apart, preferably, uniformly and vertical filling-plates D are inserted in the spaces between them at their lower portions. These plates may be secured to the ribs in any approved 65 manner and form a tight joint at their upper ends with the shell A and at their vertical edges with the opposing sides of adjacent ribs. Preferably two plates will be used, one on each side of the pipe C, and these 70 plates form the bottoms of the slag-receiving chambers, while opposing faces of adjacent ribs and that part of the shell A included between them will form three of the sides of such chambers. The other or front side must 75 be movable, and, as shown, it consists of a curved plate E, hinged at its upper end to the ribs and so shaped that when closed its lower end will abut against the plate D and its inner face fit closely against the outer face of 80 the ribs. Preferably there will be a separate front plate E for each chamber; but it is obvious that one plate may be used to close the fronts of all the chambers, or a series of plates may be employed each adapted to close 85 the fronts of two or more of the chambers. Also, preferably, there will be a projecting portion f on the plate to fit in between the opposing faces of adjacent ribs.

Some means must be provided to hold the 90 plate or plates E in closed position and also to open it or them, and one convenient way is to provide a fixed vertical guide-rod F for each plate, adjacent thereto, on which a pull-rod G is supported to slide vertically. The 95 lower end of this rod is connected to a head or block 20, which is mounted to slide upon the guide-rod F, and this head or block has one end of a link g pivotally connected to it, and the other end of such link is pivotally 100 connected to the front plate E. One pull-rod and link will be sufficient if the plate E is

used to close only one or two chambers; but if used to close more than two chambers it will be better to employ more pull-rods and links, as will be readily understood. The pull-
5 rod and link will preferably be so arranged that when the plate E is in its closed position the link will be at substantially a right angle to the guide-rod, as shown in full lines in Fig. 3. It is obvious that some detachable lock-
10 ing device may be employed to hold the push-rod in its lowest position.

For convenience in introducing the slag into the chambers a platform or floor may be constructed above the generator, as indicated
15 by H, and a series of funnels I be supported in such floor or platform, one for each chamber. The upper ends of the chambers may be partially closed or be left entirely open, as preferred.

20 It will thus be seen that I provide a series of heating-chambers on opposite sides of the generator and that three sides of each chamber are in direct contact with the water to be heated, thus affording a large area of heat-
25 ing-surface for the generator.

In operation molten slag is poured through the funnels sufficient to fill the chambers to a point just below the water-line of the boiler, and all or only a portion of such chambers
30 may be so filled. After the slag has solidified and parted with most of its heat the plate E of each chamber will be swung open by elevating the pull-rod, and the mass will fall out of the chamber. This will be facilitated by
35 the fact that the opposing sides of adjacent ribs flare outwardly and also by the fact that the slag contracts as it cools.

Referring now to Figs. 4, 5, and 6, K represents a hot-blast box, semicylindrical in
40 form and closed at both ends, except as to the inlet and outlet pipes k and k'. The box is also closed at its upper flat side, preferably by a removable cover X, and its circular portion is formed with a series of corrugations
45 or ribs B', which are similar in shape to the ribs or projections B, already referred to, except that there is no partition between their interiors and the main chamber of the box. In this apparatus the box may be conven-
50 tiently cast, so that the ribs or corrugations will be an integral part thereof. A partition-plate D', similar to those D already described, is secured to the box midway its circular portion to form the bottoms of the slag-chambers
55 on opposite sides of the box. Front plates E' are hinged at their upper ends at e' and when closed are adapted to engage the plate D' with their lower ends and the front faces of the ribs with their inner faces. They are also
60 provided with raised portions f' to fit in be-
tween opposing faces of adjacent ribs. They are similar in construction to the plates E, al-
ready described, and are connected by links
g' to pull-rods G', slidably supported on guide-
65 rods F'. A floor or platform H' is also pro-
vided, as are also funnels I', through which

the slag is poured into the chambers. In order to compel the air to contact with the heated surfaces of the corrugations, I provide a series of baffle-plates or deflectors M, which
70 may be suspended from the cover X and project into the corrugations B', thus compelling the air to follow a tortuous passage in contact with the interior faces of the ribs B'. The operation of this apparatus will, so far
75 as the use of the slag is concerned, be precisely like that of the steam-generator here-
tofore described, only it will heat air instead of water.

If preferred, each of the plates E or E' may
80 be provided with a projection O at its upper end, extending inwardly in such position that when the plate is swung open such projection will contact with the upper end of the solidified slag and force the latter out of the
85 chamber in the event it should tend to stick to the walls of the chamber.

Having thus described my invention, I claim—

1. In apparatus for utilizing slag for heat-
90 ing purposes, a receptacle provided on its ex-
terior surface with a plurality of chambers
for the reception of the slag, each chamber
partially surrounding said receptacle and
having a movable side and a filling-aperture,
95 substantially as set forth.

2. In apparatus for utilizing slag for heat-
100 ing purposes, a receptacle provided with a
plurality of ribs or corrugations on its ex-
terior surface, the opposing faces of adjacent
ribs or corrugations forming sides of a cham-
ber, a plate between adjacent ribs forming the
bottom of the chamber, and a hinged plate to
close the front of the chamber, substantially
as set forth.

3. In apparatus for utilizing slag for heat-
110 ing purposes, a receptacle provided with a
plurality of ribs or corrugations on its outer
surface, the opposing faces of adjacent ribs
flaring outwardly and forming sides of the
115 chamber, a plate between adjacent ribs forming
the bottom of a chamber, and a plate
hinged at its upper end to said ribs and adapt-
ed to abut at its lower end against said bot-
tom plate and engage with its inner face the
outer face of said ribs and form a front wall
for said chamber, substantially as set forth.

4. In apparatus for utilizing slag for heat-
120 ing purposes, a receptacle provided with a
plurality of ribs or corrugations on its exterior
surface, the opposing faces of adjacent ribs
or corrugations forming sides of a chamber, a
plate between adjacent ribs forming the bot-
125 tom of the slag-receiving chamber, a plate
hinged at its upper end to the ribs and adapt-
ed to abut at its lower end against the bot-
tom plate and engage with its inner face the
outer faces of the ribs, and means to hold the
hinged plate in its closed position, substan-
tially as set forth.

5. In apparatus for utilizing slag for heat-
130 ing purposes, a receptacle provided on its ex-

terior surface with a plurality of slag-receiving chambers, each chamber partially surrounding the receptacle and having a hinged front wall, combined with filling-funnels supported to discharge into the upper ends of said chambers, substantially as set forth.

5 6. In apparatus for utilizing slag for heating purposes, a receptacle provided on its exterior surface with a plurality of slag-receiving chambers, the front wall of each chamber being hinged at one end, combined with a fixed vertical guide-rod adjacent to said front wall, a pull-rod slidably supported on the guide-rod, and a connecting-link pivotally connected to said pull-rod and to the free end of the front wall, substantially as set forth.

10 7. In a slag steam-generator, the combination of the main shell A, a plurality of hollow ribs or projections B secured to the exterior surface of the shell, the interior of said ribs being in communication with the interior of the shell, plates fitted between adjacent ribs to form the bottoms of slag-receiving 15 chambers, movable plates to engage said bottom plates and the front faces of the ribs and form the front walls of said chambers, means to detachably lock said front plates in

closed position, and means for introducing molten slag into said chambers, substantially as set forth.

8. In apparatus for utilizing slag for heating purposes, a receptacle provided on its exterior with a plurality of slag-receiving chambers, the front wall of each chamber being hinged at its upper end, and a projection on the hinged end of the front wall projecting into the chamber to engage the solidified slag when the lower end of the wall swings open, for the purpose set forth.

35 9. In apparatus for utilizing slag for heating purposes, a receptacle provided on its exterior surface with a plurality of chambers for the reception of slag, each chamber partially surrounding said receptacle and being wider at its front than at its rear portion, and each chamber having a movable side and a filling-aperture, substantially as set forth.

40 In testimony whereof I have signed my name to this specification in the presence of two subscribing witnesses.
